UNITED STATES PATENT OFFICE.

JAMES C. WRIGHT, OF COLORADO SPRINGS, COLORADO.

ROCK-DRILL.

1,393,257.

Specification of Letters Patent. Patented Oct. 11, 1921.

Application filed August 26, 1919. Serial No. 319,384.

To all whom it may concern:

Be it known that I, JAMES C. WRIGHT, a citizen of the United States, residing at Colorado Springs, in the county of El Paso and State of Colorado, have invented certain new and useful Improvements in Rock-Drills; and I do hereby declare the following to be a full, clear, and exact description of the invention, such as will enable others skilled in the art to which it appertains to make and use the same.

This invention relates to rock drills in general, but has reference more particularly to a portable hand-actuated machine for drilling purposes including in coöperative relation, a suitable drill-steel, means for automatically rotating said steel, a reciprocating hammer, and selective means for advancing the drill steel in exact proportion to requirements of the work imposed upon it, either manually or under control of said hammer automatically.

Various devices heretofore employed either for rotating or feeding drill steels are objectionable by reason of the fact that they are constant in their operation, making no provision or allowances for abnormally hard spots or areas under treatment, and the consequent jamming or sticking of drills, with resulting injuries to the machines themselves.

An important object of the present invention is therefore, to provide most efficient drill-rotating and feeding mechanisms which will remain at rest when the drill steel sticks or becomes jammed, and which when the same is released, will again go into operation automatically.

A further object of this invention is the production of means for automatically graduating the strength of the hammer blow, from a full, heavy stroke under normal conditions, to a lighter, shorter stroke at such times as the drill steel may stick or be jammed.

A further object is the production of a compact, durable and efficient portable drill which is entirely automatic in its operation, the operator supplying the motive power only, and one in which the hammer directly governs the feed of the drill carriage, so that when the stroke of the hammer is not full or complete the feed mechanism remains at rest, and when the drill steel sticks the feed of the carriage and rotation of the

drill chuck are both brought to a standstill even though the hammer continues its movement to a limited degree.

This invention further resides in the several features of construction, general arrangement and combination of parts herein-after described and claimed.

Reference being had to the accompanying drawings which form part of this application for Letters Patent, and wherein like characters indicate corresponding parts in the several views:

Figure 1 is a side elevation of my improved rock drill;

Fig. 2 is a longitudinal, vertical, section of the invention taken centrally through the structure;

Fig. 3 is an elevation of the chuck end of the drill;

Fig. 4 is a transverse, sectional view taken on the line 4—4 of Fig. 2, showing the hammer actuating cams;

Fig. 5 is a vertical, transverse section through the hammer shank and its oppositely disposed trunnions;

Fig. 6 is a detail side elevation of the step-by-step feed drill ratchet and operative connections;

Fig. 7 is a cross-sectional view of a portion of the drill structure disclosing in side elevation the parts shown by Fig. 6;

Fig. 8 is a longitudinal, central section of the rotatable chuck;

Fig. 9 is a transverse, sectional view of drill chuck on lines 9—9 of Fig. 8;

Fig. 10 is a detail view showing a supply pipe connection for water-cooling the drill steel;

Fig. 11 is a central, vertical section through the front end of drill, showing drill chuck, the hammer head and shank, and retracting cams in position for striking a blow;

Fig. 12 is an elevation of drill mounting support showing in rear elevation a drill mounted thereon;

Fig. 13 is a plan view of a coupling socket for securing the drill structure to the drill support;

Fig. 14 is a sectional view through drill support taken on the line 14—14 of Fig. 12; and

Fig. 15 is also a transverse, sectional view through the drill support taken on the line 15—15 of Fig. 12.

In the accompanying drawings the numeral 1 indicates the drill body or casing, preferably of cast iron, provided with a longitudinal chamber 2 in which reciprocates a hammer 3. The shank or reduced stem 4 of this hammer extends rearwardly through the casing and its removable head 5. At an intermediate point within the casing 1 shank 4 is formed with a shoulder 6 between which and the inner surface of the head 5 is coiled a relatively strong compression spring 7 for the purpose of actuating the hammer. This hammer together with its stem is perforated throughout its longitudinal axis from end to end thus constituting a waterway 8 for purposes which will later appear, and communicates at its rear end with a water pipe 9 flexibly connected with a suitable source of water supply (not shown).

In advance of said shoulder 6 the hammer shank 4 is provided with a pair of oppositely disposed trunnions 10, 10, which are normally held by spring 7 against the active faces of a pair of cams 11, 11, rigidly secured to a cam-shaft 12 journaled in opposite sides of the drill casing at substantially a median position. The said trunnions 10, are each provided with renewable and relatively hardened annular bushings 13, held in place by screws 14, each having the customary driving slot in its head, and each perforated by a small pinway 15 adapted to receive a spring pressed pin 16 for locking them in position against the possibility of accidental rotation, as clearly indicated by Fig. 5.

The cams 11, 11, are spaced apart, upon their shaft 12 to permit passage of the forward portion of the hammer shank 4 as shown by Fig. 4, and are positively driven in clockwise direction, with their supporting shaft 12, by agency of a pinion 17 affixed to one end of said shaft intermeshing with a driving gear wheel 18 keyed near one end of a main driving shaft 19 also journaled in opposite sides of the casing 1.

As a means of rotating the main shaft 19 there is provided at each projecting end a removable and adjustable crank handle 20, either of which may be readily removed if desired when operating adjacent a side wall or other obstruction, the drill being operable by agency of both or either of said cranks.

This main driving shaft 19 has formed upon its surface a worm 21 constantly in mesh with a worm wheel or gear 22 upon one end of a power transmitting shaft 23 rotatably mounted in bearings 24, 25, 26, equipped at its opposite forward end with a suitably housed-in spur gear 27 as the means of rotating the drill chuck now to be described.

Inclosed within the forward portion of casing 1, a drill chuck 28 is rotatably dis-

posed, the same being provided near its outer end with a surrounding ratchet 29 engaging the spur gear 27 aforesaid, by which it is rotated as best shown by Fig. 11. This chuck, detached, is also illustrated by longitudinal and transverse sectional views, 8 and 9, respectively, from which it will be apparent that provision is made for automatically withdrawing a drill steel after each stroke of the hammer, and for permitting ready removal of the steel itself when occasion requires. To these ends the outer cylindrical chuck-casing is shouldered interiorly as at 30, and at diametrically opposite points is splined longitudinally as at 31, 31, through its rear open end to receive sliding feathers 32, 32, projecting in like relation from the rear portion of an innermost telescoping chuck member 33, also shouldered as at 34. The inner end of the outer chuck casing 28 is closed by a centrally perforated screw plug 35 after said innermost member has been inserted in splined and reciprocating relation, while interposed between the shoulders 30 and 34 of the relatively slidable chuck members is positioned a coiled spring 36 which normally but yieldingly retains said member in a retracted position. This latter or inner longitudinally slidable chuck member 33 is grooved upon opposite sides throughout its length as at 37, 37, so as to permit passage of lugs 38, projecting from opposite sides of a suitable drill steel 39, which in assembling is introduced into the chuck as indicated by Fig. 11, and then rotated to the interlocked position shown, with its rear end projecting through the central opening of closure plate 35 into the path of hammer 3.

Upon cam shaft 12 opposite its pinion 17, 105 is keyed a driving gear 40 which meshes constantly with a pinion 41 carried by a transversely arranged fly-wheel shaft 42 having secured to its opposite ends fly-wheels 43, 43, for imparting uniformity of movement to all 110 rotary parts heretofore described.

The aforesaid casing 1 surmounts an inverted, substantially T-shaped web 44, slidably arranged in the track grooves 45 of a channeled base 46 as best shown by Figs. 3 115 and 4. A feeding screw 47 is journaled in the base 46, and engages with a nut 48 depending from web 44, whereby the entire drill casing or carriage may be caused to slide freely in the track grooves 45 by rotation of said feed screw 47 in either direction. And although feed of the drill carriage and attending parts may be accomplished manually by rotation of the said screw 47 by agency of the crank handle 49, I prefer to 120 make this feed automatic by substantially the following means.

Upon the feed screw 47 is fixed a gear 50 meshing with a corresponding gear 51 affixed to one section 52 of a telescoping, sec- 130

tional or extension shaft. This tubular shaft section 52 is suitably journaled in the base 44 and telescopically receives the co-operating shaft section 53 splined or otherwise secured thereto for relative sliding or longitudinal movement only, the latter section being suitably journaled at its outermost end. The shaft section 52 is further supported at its rear end by a bracket 54 rising from a frame 55 projecting rearwardly from base 44, and is surrounded by a relatively fixed collar 56, normally held against bracket 54 by agency of a spring 57 interposed between the opposite side of said bracket and gear 51. The gear 51 is thus normally held in mesh with the gear 50, for automatic control of the latter as will later appear but when it is desired to disconnect these gears in order that feed screw 47 may be manually actuated by agency of crank 49, this is accomplished by a forward throw of shift lever 58 pivoted upon the lower end of bracket 54 and provided with a small lug 59 for engagement with a fixed pin 60 to prevent said lever falling backward.

To the advance end of slideable shaft section 53 is keyed a ratchet wheel 61, adjacent to which there is loosely mounted upon the same shaft section an adjusting lever 62 carrying a spring pressed drag pawl 63 capable of engaging the teeth of said ratchet, and above this pawl a pin 64 for retaining the lever at times in adjusted positions. Adjacent the upper portion of lever 62 a bracket 65 projects from the side of casing 1 having formed therein an arcuate slot 66 in which travels a headed guide-pin 67 also rigidly secured to and projecting from the rear of lever 62. Between the slotted portion of bracket 65 and the head of guide-pin 67 a compression spring 68 is placed for the purpose of normally retaining lever 62 in contact with the face of its slotted bracket 65, and of retaining the aforesaid adjusting pin 64 in a selected one of the series of retaining holes 69 through the bottom of bracket 65. When it is desired to transfer the pin 64 from one to another of the holes 69, this is accomplished by sliding the entire lever 62 laterally upon shaft 53, against the tension of spring 68, until said pin 64 is withdrawn, whereupon by a reversal of operation the pin may be replaced in another of the holes 69 for purposes of regulating the intermittent advance of the drill steel between each stroke as will appear in a statement of operation to follow.

As a part of the step-by-step advance feed mechanism of the drill carriage and drill steel, there is also rotatably mounted at the forward end of shaft section 53 a second or feed lever 70 spring pressed as at 71 to hold its free end normally elevated, and carrying a drag pawl 72 also spring pressed to engage the teeth of ratchet 61, while the

free end of the feed lever 70 is equipped with an anti-friction roller 73 more or less in the path of a pilot finger or cam 74, secured to and reciprocating with the drill hammer 3, through a suitable passage way 70 slotted out of the bottom of casing 1. By reference to Fig. 7 in particular, it will be seen that roller 73 is in the path of the cam finger 74. The extent of movement of lever 70 being governed by the extent of its engagement by the beveled surface of cam 74, which also regulates the rotary movement imparted to shaft 53 and through it to feed screw 47 to advance the drill carriage and steel for a fresh cut. 80

Although advancement of the drill carriage and drill steel may be accomplished manually, it will be particularly noted that provision is herein made for automatic feeding, as a matter of preference, as also increased efficiency, and that the hammer 3 controls the feed of the drill carriage. 85

Obviously the carriage may be operatively located and the drill steel positioned with reference to the rock or other material to be drilled by any approved means, but by way of exemplification I have illustrated a special form of support in detail by Figs. 12 to 15 inclusive, wherein 75 indicates a tubular body having at one end a shoe 76, and at 90 its opposite end a cross head 77, carrying pivotal nuts 78, 78, through which are threaded set screws 79, 79. Adjustably clamped upon this body member 75 is a circular undercut socket 80 one side of 100 which is bolted in position as indicated at 81 in Fig. 2, to receive a diverging circular stud 82 depending from base 46, the same being adapted to securely clamp said stud in adjusted positions. 105

The foregoing being a description of my present invention in one operative form of construction, its operation may now be briefly set forth as follows:

Having been set up, as indicated by Figs. 110 1, 2 and 12, upon a universally adjustable drill support adjacent the work to be imposed upon the invention, with its steel 39 in contact with the surface to be drilled, the main shaft 19 is rotated by agency of either 115 or both cranks 20, carrying with it driving gear 18 in a counterclockwise direction. Power is thence transmitted through intermeshing pinion 17 to the cam shaft 12, and cams 11, 11, thereon; as also through a gear 120 wheel 40 to a pinion 41, shaft 42, and fly wheels 43, 43, for well understood balancing purposes.

Rotation of cams 11, 11, thus in clockwise direction bearing upon lateral trunnions 10, 10, causes hammer 3 to slide backward against the tension of spring 7, until the trunnions aforesaid ride off said cams at the points thereof. Spring 7 thus compressed, 125 instantly shoots stem 4 and hammer 3 for 130

ward with great force, into contact with the innermost end of the drill steel 39, projecting rearwardly from the slidable inner chuck member 33 of chuck 28, the hammer then being cushioned at the termination of its active stroke by spring 36 interposed between the relatively slidable chuck members.

This operation is repeated rapidly so long as the main drive shaft 21 is rotated and during this time water for cooling and lubricating purposes may be permitted to flow in conduit 8 through the hammer stem, the hammer and the centrally perforated drill steel to its point of cutting. During this 15 operation two others of equal importance are automatically performed, to wit:

First, by agency of worm 21 upon drive shaft 19, power transmitting shaft 23, and gears 27, 29, the chuck 28 and drill steel 39 are constantly rotated; and, second, by agency of the pilot arm or cam-finger 74, moving in unison with hammer 3 to which it is attached, the feed lever 70 is engaged and depressed with each advance stroke of the 25 hammer, and therefore with each cut of the drill steel, causing a partial rotation of ratchet wheel 61, the feed shaft sections 53 and 52, gears 51 and 50, and feed screw 47, thereby advancing nut 48 and consequently 30 the entire drill carriage in exact accordance with requirements. And it will be particularly noted that such automatic advancement of the drill carriage and drill steel is governed by the depth of cut resulting from 35 each blow of the hammer, but where working conditions make necessary or advisable, an abnormally deep cut with each blow of the hammer, as for instance in relatively soft material; or on the contrary, when a 40 more limited advance of the drill steel is desirable, as in case of unusually hard rock formation, these extreme conditions are provided for by the novel and efficient operation of the adjusted lever 62 and correlative 45 parts.

While the construction and arrangement of parts hereinbefore described and illustrated by the drawings forming part of this application represents the preferred embodiment of the present invention, it will be quite obvious to persons skilled in the art to which it relates that various changes in form, size, proportion and details of construction may be made and substituted for 50 those herein set forth without in the least departing from the spirit of this invention, or sacrificing the advantages thereof.

Having thus described my present invention what I now claim and desire to secure 60 by Letters Patent is:

1. In a rock drill the combination with a drill-steel, of a chuck for holding said steel, a hammer for driving the steel, a main driving shaft, means for actuating said hammer 65 operatively connected with the main shaft,

a power transmitting shaft, worm gearing connecting said shafts, a driving gear upon said transmitting shaft, and a driven gear, surrounding the drill chuck for rotating the same by engagement with said driving gear. 70

2. In a rock drill the combination with a drill-steel, a chuck for holding said steel, a hammer, a main driving shaft, means for actuating said hammer operatively connected with the main shaft, a power transmitting shaft worm gearing connecting said shafts, a driving gear upon said transmitting shaft, a driven gear surrounding the drill chuck for rotating the same by engagement with said driving gear, and a drill 75 casing having compartments for inclosing all of the gears aforesaid.

3. In a rock drill the combination with a drill-steel, a chuck for holding said steel, a hammer, a main driving shaft, means for actuating said hammer operatively connected with the main shaft including a cam shaft upon the opposite side of said hammer from the driving shaft, a power transmitting shaft, worm gearing connecting 90 said shafts, a driving gear upon said transmitting shaft, and a driven gear surrounding the drill chuck for rotating the same by engagement with said driving gear.

4. In a rock drill the combination with a 95 drill-steel, of a chuck for holding said steel, a hammer, a main driving shaft, means for actuating said hammer operatively connected with the main shaft, a power transmitting shaft, a worm coaxial with the main 100 driving shaft, a worm-gear meshing with said worm and mounted upon said transmitting shaft, a driving gear also upon the latter shaft, and a driven gear carried by the drill chuck for rotating the same by engagement with said driving gear. 105

5. In a rock drill a reciprocating drill-actuating element in combination with a cam movable with said element, a feed mechanism, a shaft for actuating said feed mechanism, a ratchet wheel on said shaft, pawl mechanism actuated by said cam for rotating said ratchet wheel, an adjusting lever pivotally mounted on said shaft, an element carried by said lever and connected 110 with said ratchet wheel for preventing retrograde movement thereof, and means for holding the adjusting lever in predetermined positions. 115

6. In a rock drill a reciprocating drill-actuating element in combination with a cam movable with said element, a feed mechanism, a shaft for actuating said feed mechanism, a ratchet wheel on said shaft, pawl mechanism actuated by said cam for 120 rotating said ratchet wheel, an adjusting lever pivotally mounted on said shaft, a pawl carried by the adjusting lever engaging said ratchet wheel for preventing retrograde movement of the latter, and means 125 130

for holding the adjusting lever in predetermined positions.

7. In a rock drill a reciprocating drill-actuating element in combination with a 5 cam movable with said element, a feed mechanism, a shaft for actuating said feed mechanism, a ratchet wheel on said shaft, a pawl mechanism actuated by said cam for rotating said ratchet wheel, an adjusting 10 lever pivotally mounted on said shaft, an element carried by said lever and connected with said ratchet wheel for preventing retrograde movement thereof, and a bracket projecting from the drill casing for holding the 15 adjusting lever in predetermined positions.

8. In a rock drill a reciprocating drill-actuating element in combination with a cam movable with said element, a feed mechanism, a telescoping shaft for actuating 20 said feed mechanism, a ratchet wheel on said shaft, pawl mechanism actuated by said cam for rotating said ratchet wheel, an adjusting lever pivotally mounted upon the advance end of said shaft, an element carried by said lever and engaging said ratchet 25 wheel for preventing retrograde movement

thereof, and means for retaining the adjusting lever in predetermined positions.

9. A rotatable chuck for drill casings comprising in combination an outer cylindrical chuck member, an inner chuck member reciprocally mounted within said outer member and adapted to rotate therewith, a compression spring interposed between shouldered surfaces upon both chuck members, and a perforated closure for the rear end of said outer chuck member. 30

10. A rotatable chuck for drill casings comprising in combination an outer cylindrical chuck member, an inner chuck member splined within said outer member and adapted to reciprocate therein, a compression spring interposed between said relatively movable chuck members, and a centrally perforated screw closure for the inner end of said outer chuck member. 40 45

In testimony whereof I affix my signature, in presence of two subscribing witnesses.

JAMES C. WRIGHT.
